(57) **CLAIM**

The ornamental design for an automotive tire, as shown and described.

DESCRIPTION

FIG. 1 is a front perspective view of an automotive tire, according to a first embodiment;

FIG. 2 is a front elevational view thereof;

FIG. 3 is a back elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is an enlarged view of section A-A shown in FIG. 2; and

FIG. 9 is a cross-sectional view taken along line B-B shown in FIG. 8.

FIG. 10 is a front perspective view of an automotive tire, according to a second embodiment;

FIG. 11 is a front elevational view thereof;

FIG. 12 is a back elevational view thereof;

FIG. 13 is a top plan view thereof;

FIG. 14 is a bottom plan view thereof;

FIG. 15 is a right side elevational view thereof;

FIG. 16 is a left side elevational view thereof;

FIG. 17 is an enlarged view of section C-C shown in FIG. 11; and,

FIG. 18 is a cross-sectional view taken along line D-D shown in FIG. 17.

The broken lines in the drawings depict portions of the automotive tire that form no part of the claimed design. The hatching of FIG. 9 and FIG. 18 also forms no part of the claimed design.

1 Claim, 16 Drawing Sheets
